UNITED STATES PATENT OFFICE.

MARTIN D. GARNER, OF OKLAHOMA, OKLAHOMA.

RAILWAY-SWITCH MECHANISM.

1,117,997.

Specification of Letters Patent. Patented Nov. 24, 1914.

Application filed May 27, 1912. Serial No. 700,079.

To all whom it may concern:

Be it known that I, MARTIN D. GARNER, a citizen of the United States, residing at Oklahoma, in the county of Oklahoma and State of Oklahoma, have invented certain new and useful Railway-Switch Mechanisms, of which the following is a specification, reference being had to the accompanying drawings.

10 This invention has reference to the art of railway switches, and more particularly to those switches in the art, adapted to be operated by mechanism situated remotely from the switch, and which is adapted to be operated at will, by mechanism carried by a car.

It is an object of the invention to automatically throw a switch by mechanism carried by a car.

20 Another object is to give a new and desirable construction, by which friction is reduced and by which the casual operation of the switch is guarded against.

These and other similarly important objects of the invention becoming more apparent from a further reading of this specification, may be obtained through suitable forms of mechanism embodying the invention, and one of such forms is illustrated on the drawings accompanying and forming a part of this specification, whereon,

Figure 1 is a plan view of a portion of railway, showing a switch, and the invention applied to throw the same. Fig. 2 illustrates a plan view of means adapted to co-operate with mechanism, carried by a car, for operating the switch. Fig. 3 illustrates a similar view, of means for acting in conjunction with the switch, and adapted to co-operate with the means illustrated in Fig. 2. Fig. 4 illustrates a side elevation of a car; a portion of the switch throwing means, and means carried by the car for co-operating with the switch throwing means. Fig. 5

40 illustrates, perspectively, a form of means carried by the car, for throwing the switch-operating means.

45 The rails 6, ties 7, and switch-tongues 8, are, of course, of the usual type, constituting no new invention. Carried by a suitably located pivot bearing 9, preferably remote from the tongues 8, and which may be located in a suitable framing, such, for instance, as 10, which may be located between the rails 6, there is a lever 11, adapted to be moved about a pivot 9, there connected to

the switch-tongues 8 through connecting rods 12, and 13, in any suitable manner, for instance, by having the rods 12 and 13 pivoted, as at 14, to the lever 11 and as at 15 to 60 ears borne by the switch-tongues. Preferably superimposed upon the lever 11, and occupying the same pivot 9, is a bell-crank, comprising arms 16, 17 and 18, the longer one 16 of which is adapted to be retained in 65 one or the other of its operative positions, by a suitable form of locking means, which, in the present instance, may comprise a keeper 19, pivoted on the face of the lever 11, as at 20, and provided with bills 21 and 22, 70 each of which, in season, and alternately, will engage with stops 23 and 24, thus retaining the switch-tongue throwing mechanism in one or another of its operative positions. This keeper 19, may be associated 75 with the lever 11, in any suitable manner, and in the present instance is provided with arms 25 inserted slidably, in an eye 26, borne at the extremity of the lever 11 and open on the outer end of this lever to receive the 80 arm 25. The bills 21 and 22 are also adapted and arranged to move along a cam face 27 while stress is being imparted to either of the arms 17 or 18, of the bell-crank, when the thrust will be distributed through 85 the pivot 9, the pivot 20, and to the bills on the keeper 19, which, at the time, is bearing against the cam-face 27, and thus will the lever 11 be thrown, in one direction or another, to operate the switch tongue 8 to an 90 operative or inoperative position the force being communicated through the keeper, the operation of which to properly secure or release the mechanism is thus assured.

95 The lever 11, as before stated, may be operated through the arms 16, 17 and 18, for instance, by having the arms 17 and 18 connected to cables 28 and 29, which may be guided by rollers 30 and 31, through an opening formed in the framing 10, it being understood that for convenience the switch throwing mechanism thus described, may be assembled and borne in this framing. These cables 28 and 29, respectively, after passing about guides 32 and 33, are connected to the arms 34 and 35 of a spider, that is borne on a pivot 36, suitably located, for instance, in a framing 37, which is located between the rails 6, and remotely from the mechanism previously described. This spider, includes an arm 38, which bears a trip 39, in the present instance, in the form of a roller,

borne on a stud which projects through a slot 40, in the framing 37, and which will be engaged by switch throwing mechanism, carried by the car, for operating the switch. 5 This spider also includes an arm 41, to which is connected, as at 42, a bar 43, adapted to reciprocate in a bearing 44, as the spider throws from one position to another, during its operation, and for the purpose of insuring a complete throw of this spider, a spring 45, convoluted about the bar 43, will exert its force between the extremity of arm 41 and the bearing 44.

For the purpose of operating the mechanism, so far set forth, any suitable form of mechanism may be adopted, and one of such forms, comprehends a pair of racks 46 and 47, adapted to operate in guides 48 and 49 mounted on supports 50 adapted to be secured to the bolsters 51 of the car, and which are steadied by braces 52. To the lower extremities of these racks 46 and 47, respectively, are secured shoes or cams 53 and 54, which are adapted to be shifted at will alternately into the path of the element 39 in the framing 37. For the purpose of operating this rack 46 and rack 47 and the cams 53 and 54, bell-cranks 55, connected to the racks by connecting rods 56, are mounted on a bearing rod 57 journaled in bearings 58, carried by the car bolsters 51. One arm of each crank is connected to cables 59 and 60 which pass over rollers 61, borne by the bolsters, and the cables are connected to an arm 62 of bell cranks which are pivoted as at 63 to bearings 64, carried at the fore end of the car, and with which bell cranks arms 65 are associated which bear foot-pieces 66 and 67. For the purpose of normally

elevating the racks 46 and 47 and cams 53 40 and 54 out of the path of the element 39 a spring 56 may be harnessed between the car bolster and each of the racks 46 and 47. Thus it will be seen that upon pressing either foot piece 66 or 67 alternately, the cams 45 will lower into the path of the member 39, which will cause the switch to be thrown in the direction intended.

Having thus described this invention, I claim:

A switch throwing device comprising in combination a lever, a pivotal support therefor, a link for moving a switch point connected pivotally to the lever, a second lever pivoted commonly with the first lever 55 having an arm extended over the first named lever and provided with a socket open on the outer end of the arm, a keeper pivoted on the first lever outwardly of the arm and having an arm inserted slidably in the 60 socket, bills formed on the keeper projected saliently from the keeper, a cam member outwardly of the first lever having a face concentric with the pivot of the lever and disposed to receive the bills 65 coincidently and slidably thereagainst at its intermediate part, the cam terminating in shoulders for engagement with the bills at opposite limits of the movement of the first lever to prevent casual return thereof, and 70 means to operate the second lever.

Signed at Oklahoma, in the county of Oklahoma and State of Oklahoma, this 23 day of May, 1912.

MARTIN D. GARNER.
